REVERSIBLE FORCEPS

Gerald J. Lockwood, Edison, N.J., assignor to E. R. Squibb & Sons, Inc., Princeton, N.J.

Filed Oct. 27, 1971, Ser. No. 193,230

Term of patent 14 years

Int. Cl. D24—02

U.S. Cl. D83—12 R

FIG. 1

FIG. 2

FIG. 3

FIG. 4

FIG. 5

FIG. 6

FIG. 1 is a side elevational view of reversible forceps looking from the right showing my new design;

FIG. 2 is a plan view looking from the bottom of FIG. 1;

FIG. 3 is a side elevational view looking from the left of FIG. 1;

FIG. 4 is a plan view looking from the top of FIG. 1;

FIG. 5 is an elevational view looking from the right of FIG. 1;

FIG. 6 is an elevational view looking from the left of FIG. 1.

I claim:

The ornamental design for a reversible forceps, as shown.
